United States Patent Office

Des. 196,457
Patented Oct. 1, 1963

196,457

CONTAINER CLOSURE

Irvin D. Wagner, 301 E. Derry Road, Hershey, Pa.

Filed Aug. 24, 1962, Ser. No. 71,446

Term of patent 14 years

(Cl. D58—26)

I claim:

The ornamental design for a container closure, substantially as shown.
